UNITED STATES PATENT OFFICE

HENRY FREEMAN, OF TOTTENHAM, LONDON, AND HARRY DUNDONALD THURGAR, OF LONDON, ENGLAND

DEVICE FOR USE IN DRESSING THE HAIR

Application filed March 25, 1930, Serial No. 438,868, and in Great Britain March 26, 1929.

This invention relates to devices for use in dressing the hair, and has for its principal object to provide an improved, simple and effective device whereby loose ends of hair may be readily formed into a roll, the device according to the invention being especially applicable for dressing hair that has been shingled or bobbed while it is being allowed to grow to a sufficient extent to be "put-up" in the usual manner.

According to the invention, the improved device comprises a hair slide or the like provided with a clip or like member adapted to engage and hold the loose ends of hair against the inner side of the base member of the slide while the device is turned over one or more times to form the hair into a roll, and provided with means adapted to engage at the rear of the roll to maintain the formation thereof. Conveniently the device is in the form of a hair slide or clip having an auxiliary clip member adapted to engage and to hold the loose ends of hair against the inner side of the base member of the slide.

The invention is hereinafter described by way of example with reference to the accompanying diagrammatic drawings, in which:

Figure 1 is a view in side elevation illustrating one construction of hair-dressing device according to the invention;

Figure 2 is a plan view corresponding to Figure 1;

Figure 3 is a side elevation illustrating a modification;

Figure 4 is an inverted plan view corresponding to Figure 3;

Figure 5 is a view similar to Figure 1 illustrating a further modification;

Figures 6 and 7 are views similar to Figures 3 and 4 illustrating further modifications; and

Figure 8 is a side elevation illustrating a further modification.

In carrying the invention into effect according to one construction and with reference to Figures 1 and 2 of the accompanying diagrammatic drawings, the device may be made in the form of a hair slide having a curved base member 1 to which a similarly

curved clip member 2 is hinged as by means of a rivet 3 at one end. For the purpose of engaging the loose ends of hair and holding them to the base member 1 while the device is turned over and over to form a roll, an auxiliary clip member 4 is provided, such clip member 4 conveniently being pivotally connected to the parts 1, 2 by means of the rivet 3 at one end and being similarly curved. The members 1, 2, 4 preferably are made of celluloid, imitation tortoiseshell or like substance and may be of channel-like formation with the concavity on the inner side to give greater strength. The free ends of the members 1, 2 are fitted with parts 5, 6 respectively of a press-button fastening device.

According to the modification illustrated in Figures 3 and 4, the clip member 2 is formed of bent wire and is hinged at one end to the base member 1 by means of a fitting 7, while at the other end it is adapted to engage a knob or stud 8 fitted to the base member 1 adjacent the end thereof. The auxiliary clip member 4 consists of a flat strip fixed at one end to the base member 1 as by means of a rivet 9.

According to a further modification, as illustrated in Figure 5, the auxiliary clip member 4 is formed integrally with the base member 1 by bending an extending part of the latter back upon itself. The free end of the base member 1 may, as shown, have an extension 10 bent back upon itself to engage the clip members 2, 4.

According to a further modification illustrated in Figures 6 and 7, the base member 1 and clip member 2 are constructed and adapted to be connected in a manner similar to that shown in Figures 3 and 4. The base member 1 is fitted or provided with a longitudinally extending toothed or serrated inwardly projecting part 12 co-operating with a longitudinal slot 13 in the auxiliary clip member 4 so as to hold the loose ends of hair more securely. The auxiliary clip member 4 is, adjacent its free extremity, formed with a hole or aperture 14 through which the stud 8 projects for engagement with the respective portion of the wire clip member 2. The stud 8 may be formed with a flange or shoul-

der 8a or the like adapted to engage with the member 4 and retain it in the closed position so that it grips the ends of hair while rolling the same up without the necessity of holding the member 4 in place by hand.

5 In the use of such a device the outer clip member 2 is opened by disengaging the press-button or equivalent fastening, and the loose ends of hair are applied between the base member 1 and the auxiliary clip member 4 so that they may be held while the device is turned over upwardly to form the hair into a roll. When the desired size and disposition of the roll has been obtained, the outer clip member 2 is closed round the rear of the roll and is secured by means of the press-button or equivalent fastening, the roll being thereby retained in position. The hair adjacent the ends of the roll may be arranged 10 to cover the ends of the device so that it is completely hidden from view. When the ends of hair are being engaged between the base member 1 and the auxiliary clip member 4, the device conveniently is disposed with the concave side outermost or may be disposed towards the head as desired.

According to a further modification, as illustrated in Figure 8, the auxiliary clip member 4 may, as before described, be integrally formed with the base member 1 and, instead of providing an outer clip member, such as 2 in the constructions before described, the respective ends of the device are formed with holes for the reception of a pin 15 or like member which is inserted through the holes to engage the hair and thereby to retain the roll in position.

It will be understood that the invention is not limited to the details of construction hereinbefore described. For example, both 40 the inner and outer clip members may be formed of wire and may, if desired, be hinged to the base member at opposite ends. In addition, although the base member and auxiliary clip member are preferably of curved formation, they may be initially straight and may be held to the required curvature after the roll has been formed by means of the roll-retaining means. The invention enables the 45 hair to be readily and effectively dressed during the transition period from short to long hair.

What we claim is:—

1. A device for use in dressing the hair 55 comprising a base member having teeth, a clip hinged to the base member and having a slot to receive said teeth, said clip coacting with the base member to hold the loose ends of hair against the inner side of the base member while the device is rotated to form the hair into a roll, and an auxiliary clip member hinged to said base member and adapted to engage the first named clip and coact therewith to engage the rear of the roll 60 to maintain the formation thereof.

2. A device for use in dressing the hair comprising a curved base member having longitudinal teeth, a curved clip member nesting in said base member and having a slot receiving said teeth, a curved auxiliary clip member nesting in the first named clip member, a common pivot connecting the ends of all of said members at one end thereof, and a press button carried by the base member and detachably connecting together the free ends of all of said members. 70

3. A device for use in dressing the hair comprising a curved base member, a curved clip member, a curved auxiliary clip member, each of said members nesting in the curvature of the next adjacent member, a common pivot hingedly connecting the members together at one end, and a press button carried by the base member, there being a slot in said clip member receiving said press button, said auxiliary clip member being formed of spring wire looped at the free end to provide a spring loop for receiving said press button and detachably securing the free ends of all of said members together. 75
